UNITED STATES PATENT OFFICE

96,823

DESIGN FOR A VACUUM CLEANER CASING

Helen H. Dulany, Chicago, Ill., assignor to The
Electric Vacuum Cleaner Company, Inc.,
Cleveland, Ohio, a corporation of New York

Application March 13, 1935, Serial No. 55,874

Term of patent 14 years

To all whom it may concern:

Helen H. Dulany, a citizen of the United States, residing at Chicago, in the county of Cook, State of Illinois, has invented a new, original, and ornamental Design for a Vacuum Cleaner Casing, of which the following is a specification, reference being had to the accompanying drawing, forming a part thereof.

The figure is a perspective view of a vacuum cleaner casing embodying my design.

I claim:

The ornamental design for a vacuum cleaner casing, as shown.

In witness whereof, I have hereunto set my hand this 20th day of February, 1935.

HELEN H. DULANY.
